CYRA BISSELL WATTLES, OF PROVIDENCE, RHODE ISLAND, ASSIGNOR TO PROVIDENCE GAS MOTOR COMPANY, OF PROVIDENCE, RHODE ISLAND, A CORPORATION OF RHODE ISLAND.

GAS-MOTOR ENGINE.

No. 889,417.

Specification of Letters Patent.

Patented June 2, 1908.

Application filed June 12, 1906. Serial No. 321,357.

To all whom it may concern:

Be it known that I, CYRA BISSELL WATTLES, a citizen of the United States, residing at Providence, in the county of Providence and State of Rhode Island, have invented a new and useful Improvement in Gas-Motor Engines, of which the following is a specification.

This invention has reference to an improvement in gas or hydro-carbon engines and more particularly to an improvement in valve controlling mechanism for gas motor engines, reference being had to United States Letters Patent No. 509,981, issued to me December 5, 1893, for gas motor engines, to which my present invention is particularly adapted.

In the use of gas engines for automobile or similar purposes, it is required at times to instantly cut out or disconnect the engine from the running mechanism of the car and apply the brakes, when meeting a sudden or unexpected obstruction or for other causes. This sudden disconnecting of the engine, which may be running at full speed, will allow the engine to race, causing excessive wear on the running parts and liability of breaking the same, also in the usual form of gas engines having two or more cylinders, both cylinders are in operation at the same time, when at times the power of one cylinder is sufficient to do the work required, and if the power of one cylinder is cut out through the spark mechanism the operative parts of the cylinder will continue to run and will use the same amount of gas as when under working conditions, thus causing an unnecessary loss in friction and expense. This condition also requires power from the working cylinder to run the idle parts of the cut-out cylinder and to overcome the compression of the same, thus reducing the power of the working cylinder.

The object of my invention is to improve the construction of a gas engine having an outer annular cylinder, an inner circular cylinder of smaller diameter arranged concentric therewith, pistons fitted to the cylinders and intake and exhaust valves fitted to each cylinder, whereby the exhaust valve of the outer annular cylinder is controlled by a governor, which acts automatically to open the exhaust valve when the engine has reached an excessive speed and to close the same when the engine has returned to its normal speed.

A further object of my invention is to pro-

vide the engine with mechanism operated by a foot or other form of lever whereby the exhaust valve of the outer annular cylinder may be opened and the engine run by the inner circular cylinder and its operative parts, when the power of one cylinder is sufficient to do the work required.

A still further object of my invention is to automatically cut out the sparking to the outer annular cylinder when the exhaust valve is opened and to automatically connect the same when the exhaust valve is released.

My invention consists in the peculiar and novel construction of a gas motor engine having an outer annular cylinder, an inner circular cylinder of smaller diameter arranged concentric therewith, pistons fitted to the cylinders and connected to the crank shaft, intake and exhaust valves fitted to each cylinder, a governor, mechanism operatively connected with the exhaust valve for the outer annular cylinder and the governor, whereby the exhaust valve is automatically opened when the engine reaches an excessive speed and closes when the engine has returned to its normal speed, mechanism adapted to be operated by a lever and operatively connected to the exhaust valve, and an electric switch operatively connected with the exhaust valve mechanism and a source of electric energy (not shown), whereby on opening the exhaust valve by the mechanism the engine is run by the inner cylinder and its operative parts, with details of construction, as will be more fully set forth herein- after and claimed.

Figure 1 is a vertical side view of the engine showing the head, cylinders and pistons in section, the automatic exhaust valve opening mechanism intermediate the valve and the governor in the position it would assume with the engine stopped, the foot lever mechanism for opening the exhaust valve in its normal position, and the electric switch in the closed position. Fig. 2 is a detail view partly in section of the automatic exhaust valve opening mechanism, showing the same in the position it would assume in opening the exhaust valve, the foot lever valve opening mechanism in its normal position, and the electric switch in the open position, and Fig. 3 is a detail sectional plan view of the exhaust valve opening mechanisms taken on line 3 3 of Fig. 2.

In the drawings, a indicates part of the

chassis of an automobile, *b* the frame of the engine (which is of the four cycle type) supported on the chassis, *c* the crank shaft supported in suitable bearings in the frame, *d* the crank disks shown in broken lines in Fig. 1, *e* the connecting rod, *f* the annular external cylinder, *g* the stationary piston, *h* the head, *i* the inner trunk cylinder pivotally secured to the connecting rod *e* and forming the annular piston *k*, *l* and *m* the automatic intake valves, *o* and *p* the mechanically operated exhaust valves, *r* the governor, *s* a link connecting the automatic exhaust valve opening mechanism intermediate the exhaust valve *o* and the governor *r*, *t* the foot lever exhaust valve opening mechanism operatively connected with the exhaust valve *o*, and *v* the electric switch of my improved gas motor engine.

The intake valve *l* controls an intake port which opens into the annular external cylinder *f*. The intake valve *m* controls an intake port which opens into the trunk cylinder *i* through the stationary piston *g*. The exhaust valve *o* controls an exhaust port which leads from the annular external cylinder *f*, and the exhaust valve *p* controls an exhaust port which leads from the trunk cylinder *i* through the stationary piston *g*, as shown in Fig. 1. The exhaust valves are operated mechanically by mechanism connected with the engine shaft *c* in the usual way. Each cylinder has a spark plug connected by wires to a source of electric energy and a timer, not shown. The action of each cylinder is the same as any four cycle gas engine, the explosions taking place alternately in the cylinders, thus giving a working stroke for each revolution of the engine.

The governor *r* has the usual balls 44 connected to the vertical shaft 5 by the pivoted links 6 and to the sleeve 7 by the links 8. The shaft and sleeve are rotatably supported in the bearings 9 on the engine frame and the shaft is revolved by a train of gears 10 operatively connecting the shaft 5 with the engine shaft *c*, as shown in Fig. 1.

The automatic exhaust valve opening mechanism *s* consists of a short horizontal arm 11 in which the lower end of the sleeve of the governor is rotatably secured, a vertical arm 12 pivotally secured at its upper end to the arm 11, a toggle lever 13 pivotally secured to a fixed stud 14, a toggle lever 15 having the slot 16, and the L-shaped end 17 in which is the slot 18 pivotally supported at its L-shaped end by a pin 19 on a fixed stud 20 and extending through the slot 16 and pivotally secured together at their adjoining ends and to the lower end of the vertical arm 12 by a pin 21. A horizontal bar 22 having the cam-shaped end 23 reciprocally supported in the bearings 24 and 25 in a position to bring the cam end 23 under the stem of the exhaust valve *o*, a block 26 hav-

ing the side pin 27 and the set bolt 28 is adjustably secured to the bar 22 by the set bolt 28 in a position for the pin 27 to enter the slot 18 in the L-shaped end of the toggle lever 15. A bell crank lever 29, having the vertical arm 30 and the horizontal arm 31 in the end of which is a slot 32, is pivotally secured to a fixed stud 33 in a position for the pin 21 in the adjoining ends of the toggle levers 13 and 15 to enter the slot 32 in the end of the arm 31 and a weight 34 secured to the lower end of a rod 35 which is pivotally secured at its upper end to the end of the arm 30 of the bell crank lever 29, as shown in Figs. 1 and 2.

The foot lever exhaust valve opening mechanism *t* consists of a horizontal bar 36 having a cam-shaped end 37 corresponding to the cam end 23 on the bar 22 and reciprocally supported in the bearings 24 and 25 in a position to bring the cam end 37 under the stem of the exhaust valve *o*, as shown in Fig. 2. The opposite end of the bar 36 is pivotally connected to a foot lever 38 which is pivotally secured to a fixed support 39. A coiled spring 40 is connected to the bar 36 and to a fixed support, the tension of the spring holding the bar in its normal position. The block 26 is adjusted on the bar 22 so as to give a clearance or lost motion between the cam end 23 and the stem of the exhaust valve *o*, thus allowing the engine to run at its normal speed without opening the valve.

The electric switch *v* consists of an insulating block 41 secured to the chassis *a* and having the contact points 42 and 43 and a spring contact arm 44 having the T-shaped end 45 and secured to the horizontal bar 22 of the exhaust valve mechanism *s* in a position for the T-shaped end to engage automatically with the contact points 42 and 43 and close the circuit, when the exhaust valve mechanism *s* is in its inoperative position, as shown in Fig. 1, or to open the circuit when the exhaust valve mechanism is in its operative position, as shown in Fig. 2. A wire 46 leads from a source of electric energy (not shown) to the contact point 43, and a wire 47 leads from the contact point 42 to a spark plug (not shown) connected to the outer annular cylinder *f*.

When the engine increases in speed or commences to race by the disconnecting of the engine from the driving mechanism of the car, or when both cylinders are giving an excess of power or speed beyond that required to do the work, the balls of the governor are thrown outward by the increased centrifugal force beyond their normal running position and through the arms 11 and 12 the toggle levers 13 and 15 move the bar 22 with the cam end 23 which engaging with the stem of the exhaust valve *o* opens the valve *o* and the switch *v*, as shown in Fig. 2, and automatically cuts out the outer annular cylinder 130.

5. When the power of the cut-out cylinder is again required the mechanism acts automatically in a reverse direction and the valve and switch close through the governor resuming its normal running position. The exhaust valve *o* is also opened at any time required independent of the governor by moving the foot lever 38 which acting through the bar 36 brings the cam end 37 into engagement with 10 the stem of the exhaust valve and opens the same. When the pressure of the foot is removed from the lever the tension of the springs 40 moves the lever and bar 36 back to their normal position and releases the valve, 15 which closes through the tension of the usual coiled spring on the stem of the valve, as shown in Fig. 1.

It is evident that the construction of the mechanism intermediate the exhaust valve *o* 20 and the governor *r* could be varied without materially affecting the spirit of my invention.

Having thus described my invention, I claim as new and desire to secure by Letters 25 Patent:—

1. A gas engine having an outer annular cylinder, an inner circular cylinder of smaller diameter arranged concentric therewith, pistons fitted to the cylinders, intake and exhaust valves connected to each cylinder, a governor, and mechanism intermediate one of said valves and the governor, whereby on the engine attaining an excessive speed the said valve is opened automatically and the 35 power of the engine reduced to one cylinder.

2. A gas engine having an outer annular cylinder, an inner circular cylinder of smaller diameter arranged concentric therewith, pistons fitted to the cylinders, intake and exhaust valves connected to the outer annular cylinder, intake and exhaust valves connected to the inner circular cylinder, an electric switch, a governor, and mechanism operatively connecting the exhaust valve on the 45 outer annular cylinder with the governor, whereby on the engine attaining an excessive speed the exhaust valve and switch are opened automatically and the power of the engine reduced to the power of one cylinder, 50 as described.

3. A gas engine having an outer annular cylinder, an inner circular cylinder of smaller diameter arranged concentric therewith, pistons fitted to the cylinders, intake and exhaust valves connected to the outer annular cylinder, intake and exhaust valves connected to the inner circular cylinder, a governor, mechanism operatively connecting the exhaust valve on the outer annular cylinder 60 with the governor, and mechanism operatively connecting the exhaust valve on the outer annular cylinder with a lever, whereby the exhaust valve is opened or closed automatically or by operating the lever, for the 65 purpose as described.

4. The combination with a gas engine having an outer annular cylinder, an inner circular cylinder of smaller diameter arranged concentric therewith, pistons fitted to the cylinders, intake and exhaust valves connected to each cylinder and a governor, of an automatic exhaust valve opening mechanism comprising a short horizontal arm 11 in which the lower end of the governor sleeve is rotatably secured, a vertical arm 12 pivotally secured at its upper end to the arm 11, a toggle lever 13 pivotally secured to a fixed stud, a toggle lever 15 having the slot 16, and the L-shaped end 17 in which is the slot 18 pivotally supported at its L-shaped end by a pin 19 on a fixed stud and extending through the slot 16 and pivotally secured together at their adjoining ends and to the lower end of the arm 12 by a pin 21, a horizontal bar 22 having the cam shaped end 23 reciprocally supported in bearings in a position to bring the cam end 23 under the stem of the exhaust valve on the outer annular cylinder, a block 26 having the pin 27 and a set bolt adjustably secured to the bar 22 by the set bolt in a position for the pin 27 to enter the slot 18 in the L-shaped end of the toggle lever 15, whereby the exhaust valve is opened or closed automatically for the purpose as described.

5. The combination with a gas engine having an outer annular cylinder, an inner circular cylinder of smaller diameter arranged concentric therewith, pistons fitted to the cylinders, intake and exhaust valves connected to each cylinder, and a governor, of an automatic exhaust valve opening mechanism comprising a short horizontal arm 11, in which the lower end of the governor sleeve is rotatably secured, a vertical arm 12 pivotally secured to the arm 11, a toggle lever 13 pivotally secured to a fixed stud, a toggle lever 15 having the slot 16 and the L-shaped end 17 in which is the slot 18 pivotally supported at its L-shaped end by a pin 19 on a fixed stud through the slot 16 and pivotally secured together at their adjoining ends and to the end of the arm 12 by a pin 21, a horizontal bar 22 having the cam-shaped end 23 reciprocally supported in bearings in a position to bring the cam end 23 under the stem of the exhaust valve on the outer annular cylinder, a block 26 having the pin 27 and a set bolt adjustably secured to the bar 22 by the set bolt in a position for the pin 27 to enter the slot 18 in the L-shaped end of the toggle lever 15, a bell crank lever 29 having the vertical arm 30 and the horizontal arm 31 in the end of which is a slot 32 pivotally secured to a fixed stud in a position for the pin 21 in the toggle levers to enter the slot 32 in the arm 31, a weight 34 secured to a rod 35 which is pivotally secured at its upper end to the end of the arm 30 of the bell crank lever, a bar 36 having a cam-shaped end 37 reciprocally supported in bearings in a position to 130

bring the cam end 37 under the stem of the exhaust valve, a foot lever 38 pivotally secured to the opposite end of the bar 36 and to a fixed support, and a coiled spring 40 attached to the bar and to a fixed support, whereby the exhaust valve is opened or closed automatically or by the lever 38 for the purpose as described.

6. The combination with a gas engine having an outer annular cylinder, an inner circular cylinder of smaller diameter arranged concentric therewith, pistons fitted to the cylinders, intake and exhaust valves connected to each cylinder and a governor, of an automatic exhaust valve opening mechanism comprising a short horizontal arm 11 in which the lower end of the governor sleeve is rotatably secured, a vertical arm 12 pivotally secured at its upper end to the arm 11, a toggle lever 13 pivotally secured to a fixed stud, a toggle lever 15 having the slot 16, and the L-shaped end 17 in which is the slot 18 pivotally supported at its L-shaped end by a pin 19 on a fixed stud and extending through the slot 16 and pivotally secured together at their adjoining ends and to the lower end of the arm 12 by a pin, a horizontal bar 22 having the cam shaped end 23 reciprocally supported in bearings in a position to bring the cam end 23 under the stem of the exhaust valve on the outer annular cylinder, a block 26 having the pin 27 and a set bolt adjustably secured to the bar 22 by the set bolt in a position for the pin 27 to enter the slot 18 in the L-shaped end of the toggle lever 15, a bell crank lever 29 having the vertical arm 30 and the horizontal arm 31 in the end of which is a slot 32 pivotally secured to a fixed stud in a position for the pin 21 in the toggle levers to enter the slot 32 in the arm 31, a weight 34 secured to a rod 35 which is pivotally secured at its upper end to the end of the arm 30 of the bell crank lever, a bar 36 having a cam-shaped end 37 reciprocally supported in bearings in a position to bring the cam end 37 under the stem of the exhaust valve, a foot lever 38 pivotally secured to the opposite end of the bar 36 and to a fixed support, and a coiled spring 40 attached to the bar and to a fixed support, whereby the exhaust valve is opened or closed automatically or by the lever 38, and a switch controlled automatically, for the purpose as described.

7. The combination with a gas engine having an outer annular cylinder, an inner circular cylinder of smaller diameter arranged concentric therewith, pistons fitted to the cylinders, intake and exhaust valves connected to each cylinder, and a governor, of

an automatic exhaust valve opening mechanism comprising a short horizontal arm 11, in which the lower end of the governor sleeve is 55 rotatably secured, a vertical arm 12 pivotally secured to the arm 11, a toggle lever 13 pivotally secured to a fixed stud, a toggle lever 15 having the slot 16 and the L-shaped end 17 in which is the slot 18 pivotally supported at 60 its L-shaped end by a pin 19 on a fixed stud through the slot 16 and pivotally secured together at their adjoining ends and to the end of the arm 12 by a pin 21, a horizontal bar 22 having the cam shaped end 23 reciprocally 65 supported in bearings in a position to bring the cam end 23 under the stem of the exhaust valve on the outer annular cylinder, a block 26 having the pin 27 and a set bolt adjustably secured to the bar 22 by the set bolt in a position for the pin 27 to enter the slot 18 in the L-shaped end of the toggle lever 15, a bell crank lever 29 having the vertical arm 30 and the horizontal arm 31 in the end of which is a slot 32 pivotally secured to a fixed stud in a position for the pin 21 in the toggle levers to enter the slot 32 in the arm 31, a weight 34 secured to a rod 35 which is pivotally secured at its upper end to the end of the arm 30 of the bell crank lever, 80 a bar 36 having a cam-shaped end 37 reciprocally supported in bearings in a position to bring the cam end 37 under the stem of the exhaust valve, a foot lever 38 pivotally secured to the opposite end of the bar 36 and 85 to a fixed support, and a coiled spring 40 attached to the bar and to a fixed support, whereby the exhaust valve is opened or closed automatically or by the lever 38, and a switch controlled automatically, for the purpose as described.

In testimony whereof I have signed my name to this specification in the presence of two subscribing witnesses.
